FIG. 1.

FIG. 2.

Inventor

G. H. Deaton.

UNITED STATES PATENT OFFICE.

GEORGE H. DEATON, OF CHICAGO, ILLINOIS.

CALENDAR.

1,117,802.

Specification of Letters Patent.

Patented Nov. 17, 1914.

Application filed December 15, 1913. Serial No. 806,807.

To all whom it may concern:

Be it known that I, GEORGE H. DEATON, a citizen of the United States, residing at Chicago, in the county of Cook and State 5 of Illinois, have invented a new and useful Improvement in Calendars, of which the following is a specification.

This invention relates to a combined reference and memorandum calendar, the reference calendar being placed upon one side of the sheet and being similar to wall calendars in ordinary use so far as the arrangement of the printed matter is concerned while the memorandum side is upon the reverse of the sheet and is provided with suitable spaces to contain written memoranda, these spaces corresponding to the days of the month as shown upon the reference side, but running reversely with respect to dates. 10 The object of the invention is to provide a calendar upon which various notes may be made, said notations being placed upon the back of the sheet instead of the front, and being therefore hidden from public inspection. 15 This also provides a calendar in which ample space is provided for writing various facts, such as engagements and the like without at the same time increasing the size of the sheet beyond the usual proportion or decreasing the size of the date numerals usually employed in display calendars. 20

With these and other objects in view, the invention consists of the novel features hereinafter described, pointed out in the claims and shown in the accompanying drawings, in which;

Figure 1 is a face view of a calendar with the various sheets hanging in their original 40 or normal positions, the upper portion of the calendar being broken away. Fig. 2 is a face view of a portion of said calendar showing one of the sheets reversed to bring the reference face of the sheet into view. Fig. 3 is an edge view of a portion of the calendar showing one sheet in the position occupied while being reversed. Fig. 4 is a section on the line 4-4 of Fig. 2. Fig. 5 is a detail perspective view of one of the 45 holding hooks. 50

In these drawings, 1 represents a suitable back provided with an eye 2 by means of which it may be hung from a suitable support upon a wall. This back is preferably

of a comparatively stiff card board and 55 may be of any desired size and the part not covered by the calendar sheets to be described hereafter will be employed for the printing of advertisements. Upon the back of the sheet 1 are secured adjacent opposite 60 edges small horizontally arranged pins 3, said pins being preferably secured in position by means of a piece of flexible fabric 4 glued or otherwise secured to the back of the sheet 1. These pins form pivots upon 65 which are mounted suitable wire hooks 5; said hooks pass through the sheet 1, and are bent to form a vertical U-shaped portion 6, the lower end of which is then bent inwardly with respect to the edge of 70 the sheet as shown at 7, and thence bent back upon itself as shown at 8, the backwardly bent portion extending to the edge of the sheet and being then bent rearwardly as shown at 9 so as to overlap the edge. 75

The calendars are printed as usual upon twelve sheets, and each of said sheets is provided with a memorandum face 10 and a reference face 11. I do not desire to be limited to any particular arrangement of 80 the printed matter upon these sheets, and in the drawing I have indicated a convenient arrangement, the face 10 being provided with suitable spaces to receive rings, said spaces having numerals above them corresponding to the dates printed upon the reference side of the sheet, but arranged reversely with respect to the top and bottom of the sheet. Each sheet is provided with vertical slots 12 adjacent its side edges the 90 ends of the slots being slightly enlarged, and these slotted portions are reinforced upon the face 10 by means of strips of cloth or other suitable material as indicated at 13. 85

The sheets thus described are hung upon 95 the shank portion of the hook 5 with their side edges resting between the bent portions 9 of the hook members while the loop portions formed by the members 7 and 8 bear upon the outermost sheet, and are held in engagement with said sheet, and the sheets thus held fall against the back sheet 1 by reason of the weight of the calendar sheets upon the pivoted hooks. 100

The rearwardly bent portions 9 of the 105 hooks serve as guides between which the sheets slide as they are lifted upwardly, thereby preventing the slots 12 from open-

ing to such an extent as to permit the sheets to be accidentally disengaged from the hook members.

When the calendar is delivered all of the 5 sheets lie flat and the face 10 of the January sheet will be outermost. The said sheet is drawn upwardly until the bottom of the slots reach the shank 5 of the hook, and the sheet is then drawn outwardly and down- 10 wardly so that it rests in the U-shaped bow portions 6, as illustrated in Figs. 3 and 4, this operation reversing the sheet and bringing the face 11 in front. When a memorandum is to be made upon the calendar the 15 sheet is lifted up against the back 1, the proper notation made upon the face 10 and the sheet 10 permitted to drop back into the position shown in Fig. 4. At the expiration of the month the February sheet is then 20 lifted upwardly, brought over into loop 6, reverses and falls into place upon the January sheet, and this operation is continued until all twelve sheets rest in the loop 6. All of the sheets can then be returned to 25 their normal position, thereby again bringing all of them flat against the back sheet 1 and with the faces 12 uppermost and the calendar can then be lifted for future reference.

30 What I claim is:—

1. In a calendar, reversible sheets having printed matter upon each face, said sheets being vertically slotted adjacent opposite edges, supporting means for the sheets having vertically arranged bow portions, the bow portions extending through said slots, each sheet being independently movable upwardly with respect to said bow portions, and then movable outwardly and down-

wardly along said bow portions, said sheet 40 describing an arc and being thereby re- versed.

2. A calendar comprising a back sheet, hooks pivotally connected to said back sheet and arranged in a vertical plane, and re- 45 versible calendar sheets, each of said calendar sheets being vertically slotted, said hooks projecting through said slots and the said sheets depending in one position from one portion of the hook and in reversed 50 position from another portion of the hook.

3. In a calendar, the combination with a back, of hooks pivotally carried by said back, said hooks having bow portions ar- 55 ranged vertically and at right angles to the back, calendar sheets adapted to have print- ed matter on each face, said sheets being adapted to be hung upon the upper portion of said hooks, and being vertically slotted for movement vertically with respect to said hooks, said sheets being adapted to be drawn upwardly and then swung outwardly and downwardly and to pass onto the lower por- 60 tions of said hooks thereby reversing their faces, as and for the purpose set forth. 65

4. In combination with a calendar back, hooks pivotally carried by the back ar- 70 ranged in a vertical plane at right angles to the back, and reversible calendar sheets ver- tically slotted, said hooks passing through said slots and the sheets resting in one po- sition upon the upper portion of the hooks, and when reversed resting upon the lower portion of said hooks.

GEORGE H. DEATON.
